UNITED STATES PATENT OFFICE.

BENJAMIN F. BLESSING, OF WAYNESBORO, PENNSYLVANIA.

WINDOW-SHADE STRIP.

Specification of Letters Patent. Patented July 17, 1917.

1,233,966.

Application filed October 20, 1916. Serial No. 126,751.

To all whom it may concern:

Be it known that I, BENJAMIN F. BLESSING, a citizen of the United States, residing at Waynesboro, in the county of Franklin and State of Pennsylvania, have invented new and useful Improvements in Window-Shade Strips, of which the following is a specification.

This invention relates to window shades and particularly to a strip secured along the bottom edge of the shade.

The object of the present invention is to provide a strip which may be cheaply manufactured and easily secured to the bottom edge of a window shade, without the use of stitching.

Another object of the invention is to provide a window shade with a light and durable strip in order to prevent breakage, and to increase the wear of the curtain by preserving the strip.

With the above and other objects in view the invention consists of a strip preferably of metal folded to form parallel side bars, 25 a flange formed along the edge of the said bars for contact with the folded portions of the window shade and a method of folding the shade so as to entirely conceal the strip and be clamped securely between the parallel 30 bars.

In the drawings;

Figure 1 is an elevation of the lower portion of a window shade having the improved strip applied thereto;

Fig. 2 is a transverse sectional view 35 through the strip and a portion of the shade;

Fig. 3 is a similar view taken through the hollow rivet, by means of which a cord or ring may be secured;

Fig. 4 is a cross sectional view of the strip before folding;

Fig. 5 is a similar view of the strip with the inturned flanged edges; and

Fig. 6 is a view of the strip folded before 45 its application to the shade;

Fig. 7 is a detailed elevation showing the different means for securing a ring to the curtain strip; and

Fig. 8 is a transverse sectional view through the same.

In providing a window shade with the usual wooden strip, it is necessary to fold the curtain and stitch the same in order to form a pocket for the reception of the strip, and it has been found that this method has many disadvantages. Chief among these disadvantages is the fact that the stitching weakens the curtain and causes it to tear along the line of stitching, and also the wooden strip is frail and is often broken causing the curtain to tear and preventing its further use.

The present invention aims to overcome all of these disadvantages, and to this end there is provided a metal strip 1 bent longitudinally as at 2 to form parallel side bars 3. These bars 3 are further bent inwardly along their edge to provide inturned flanges 4 to present a rounded edge to the curtain in order to prevent the side bars from cutting or injuring the same along its folded portions. The curtain is shown at 5, and is clamped between the bars 3, and is folded upon itself as at 6 to provide a portion 7 which entirely surrounds and conceals the strip 1. The end of the portion 7 is folded over one of the flanges 4 as shown at 8 and projects inwardly between the bars 3 as shown at 9, in order that this edge may be securely held and prevented from raveling. The integrally turned flanges 4 also serve to space apart the side bars 3, the space between the side bars below these flanges serving to accommodate the folded portion and end of the curtain.

After the shade is secured to the strip in the above described manner, the strip is tightly clamped to bring the parallel bars 3 together, and if desired a hollow rivet 10 may be then secured within an opening provided in the strip for the purpose of securing a cord, ring, tassel or other device thereto.

From the foregoing description when taken in connection with the accompanying drawings it will be seen that the invention

provides a neat, simple and cheap strip for shades, and one that will materially increase the life of the shade.

Having described the invention, what I claim is;

The combination with a window shade, of a metal strip folded upon itself to provide parallel side bars, the edges of which are bent inwardly to contact with the inner

side of the said bars to provide parallel spacing flanges whereby, a space is formed within the side bars and below the spacing flanges for the accommodation of the folded portion and the end of the shade, the said shade entirely inclosing the metal strip. 10 15

In testimony whereof I affix my signature.

BENJAMIN F. BLESSING.
